FINGER RING OR THE LIKE

Adolph Katz, Providence, R. I., assignor to Coro, Inc.,
New York, N. Y., a corporation of New York

Application February 25, 1955, Serial No. 34,709

Term of patent 7 years

(Cl. D45—10)

FIG. 1

FIG. 2

FIG. 3

FIG. 4

Fig. 1 is a plan view of a finger ring or the like showing my new design.

Fig. 2 is an edge view thereof.

Fig. 3 is a side elevational view of the finger ring as shown in Fig. 1.

Fig. 4 is the opposite side of Fig. 3.

I claim:

The ornamental design for a finger ring or the like, substantially as shown.
